UNITED STATES PATENT OFFICE.

LARS JENSEN, OF CHICAGO, ILLINOIS.

BOTTLING-MACHINE.

No. 883,959.

Specification of Letters Patent.

Patented April 7, 1908.

Application filed January 2, 1907. Serial No. 350,468.

To all whom it may concern:

Be it known that I, LARS JENSEN, subject of the King of Norway, residing at Chicago, in the county of Cook and State of Illinois, have invented certain new and useful Improvements in Bottling-Machines, of which the following is a specification.

My invention relates to appliances designed for bottling liquids and has special reference to apparatus adapted to fill a number of bottles simultaneously.

The chief objects of my improvement are to provide a bottling machine that will produce the necessary mechanical movements automatically; to arrange the mechanism for use with power so as to give a constant action and a uniform result; to furnish an automatic bottling machine that will perform the required functions in an efficient and expeditious manner, and to produce a device for the purpose stated that will be simple in design and having few parts will thus be less liable to get out of order.

Further objects of my invention are to so construct the parts with which the liquid comes in contact that they will be readily accessible for the purposes of cleansing and sterilizing; to provide a vent tube for the escape of air from the receptacle when being filled; and to cause the liquid to impinge against the sides of the bottle in order to eliminate the tendency to foam which is a defect commonly found in apparatus used for bottling milk.

I obtain the above and other minor results by the use of the apparatus illustrated in the accompanying drawings which form a part of this specification.

While I have shown and described my invention as arranged for filling bottles with milk, I do not wish to be limited to the precise function herein detailed, for it will be evident that my apparatus may be readily adapted for filling containers other than bottles and with any liquid desired.

In the drawings:—Figure 1 is a side elevation of my improved bottling machine adapted to fill milk bottles automatically; Fig. 2 is a top plan view with the tank and car removed; Fig. 3 is an end elevation, and Fig. 4 is an enlarged fragmentary view in section of one of the filling tubes and attachments.

Referring to the drawings 5 indicates the supports, 6 the side members and 7 the cross ties of the main frame above which is located

a supply tank 8 carried on supports 9 fixed to the main frame. Arranged transversely to the latter is the driving shaft 10 upon one end of which are mounted fast and loose pulleys 11 and upon the other end is secured a crank disk 12. Parallel with the main shaft 10 and situated beneath the tank is journaled a counter shaft 13 upon which is mounted a ratchet wheel 14, and a gear wheel 15 both fixed to said counter shaft. To the outer end of the latter is loosely mounted a ratchet lever 16, which carries a pawl 17 and is actuated by a connecting rod 18, pivoted at 19 to the said ratchet lever, and having an adjustable connection 20, in a slot 21 in said disk 12. Upon each side of the counter shaft 13 is mounted a shaft 22 carrying at one end a pinion 23 which meshes with the gear 15. To the middle of the shafts 22 are fixed gears 24.

To the inner faces of the frame supports 5 are secured angle irons 25 which extend longitudinally, and form a track upon which a car 26, designed to transport the bottles to be filled, is adapted to roll by means of wheels 27. This car may be made of any desirable length to hold a large number of bottles, and is provided beneath its floor with a gear rack 28 arranged in the median line and adapted to be engaged by the wheels 24 when said rack is brought in contact therewith by being manually pushed along the track, after which, and so long as the rack is in engagement with either of said gear wheels 24 the movement of the car will be automatic.

The bottom 29 of the tank 8 is apertured to permit of the introduction of a series of filling tubes 30 arranged transversely to the line of movement of the car 26. The said filling tubes are fixed in the tank bottom, and are open at both ends so that the liquid may pass freely therethrough. Surrounding each filling tube is a telescoping sleeve 31 likewise open at each end and adapted to reciprocate upon the filling tube with a liquid tight engagement. The lower end of each sleeve 31 is normally closed by a disk-valve 32, the margin of which is beveled to engage a similarly formed valve seat 33 in the lower end of the reciprocating sleeve 31. The latter is normally held in closed position against the valve by a coiled spring 34 which surrounds the sleeve and engages, at its lower end, a flange 35 secured to the sleeve, and its at upper end is received within a retaining ring 36 secured to the under side of

the tank bottom. The flange 35 has a raised margin 35^a to prevent lateral displacement of said spring. The flange 35 also serves as a stop which when the valve is opened engages the lip 37 of the bottle 37^a placed beneath it and thus limits the downward movement of said reciprocating sleeve. A gasket 38 insures a liquid tight connection with the margin of the bottle to be filled when the flange is in contact therewith. Each of the said valves 32 is provided with a vertical stem 39 which extends upward through the filling tube 30 and projects above the upper margin of the supply tank. These valve stems are each furnished with a longitudinal bore or vent 40 and are secured rigidly to a vertically reciprocating cross head 41 which moves in slots 42 in guides 43 fixed to the tank walls. I prefer to construct the cross head as shown with the valve stems extending therethrough, to render a substantial support for the stems and to allow free passage of air through the vent 40. The cross head 41 is operated by vertical arms 44 one on either side of the tank, attached at their upper ends to the cross head 41 by pivot pins 45, and at their lower ends are attached by crank pins 46 to crank gears 47. These crank gears are actuated by duplicate mechanism placed on opposite sides of the tank and operated from sprocket wheels 48 keyed to the main driving shaft. Sprocket chains 49 connect said wheels 48 with similar sprockets 50 journaled on studs 51 secured to the side of the tank. Connected with each sprocket 50 is a crank disk 52 provided with a crank pin 53 adjustable in a radial slot in said disk. Attached to this pin by one end is a connecting link 55 the other end of which is pivoted at 56 to the end of a ratchet arm 57 journaled on a stud 58. The arm 57 has a dog 59 which engages a ratchet 60 carried on the said stud 58 and upon the same bearing is secured a gear wheel 61 which meshes with the teeth of the said crank gear 47.

A gage consisting of a tube 62 affixed to the tank and communicating with its interior at both ends, serves as an indicator by means of which the amount of liquid in the tank can be readily determined by observation.

It will be evident that the movements of the valves in opening and closing must be synchronous with the travel of the car and that these movements must be both uniform and intermittent, *i. e.* while the valves are open and the bottles are filling the car must be held stationary and while the car is moving to bring another line of bottles beneath the filling tubes the valves must remain closed.

The required movements are produced in the following manner: When the crank pin 20 is moving from right to left as seen in Fig. 1 the pawl 17 will actuate the ratchet 14 carrying with it the gear 15 which meshing with the

pinions 23, will rotate the toothed wheels 24, both moving in the same direction which is opposite to the movement of the disk 12. If the rack 28 of the car is in engagement with one or both of said wheels their motion will carry the car along its track from left to right. This movement of the wheels 24 being so regulated by the relative pitch of the gears, and the adjustment of the pin 20 as to cause the car 26 to move just far enough to bring a fresh line of empty bottles directly beneath the outlet tubes. The arm 16 having reached its furthest limit to the left, it will then be carried back to its initial position and during this movement the train of gears 15, 23, 24, 75 will be at rest and the car will remain stationary. It is during this interval that the downward movement of the cross head 41 takes place to open the valves and allow the liquid to flow into the bottles followed by the upward movement to close the valves. Immediately following the closure of the valves the crank pin 20 will have completed one revolution and will again actuate the ratchet 14 during its next succeeding half revolution 80 in the manner already described.

The containers or bottles are arranged in transverse rows in the car or carrier and are spaced apart in each row to correspond with the spaced outlet tubes, which depend from the under side of the tank. The carrier is moved along the track until the rack engages the first gear wheel, the first row of bottles being then directly beneath the valves. As the cross head 41 descends all the valves will be simultaneously lowered, the sleeves 31 following them in their downward movement, impelled by the springs 34 until said sleeves are arrested by the engagement of their gaskets against the upper margins of the bottle lips where they are firmly held by the said springs to prevent leakage at this joint while the valve disk descends until it takes the position indicated by the dotted lines in Fig. 4. The liquid will then pass down into the bottle around the periphery of the valve disk forcing the air out through the vent 40 in the valve stem 39. As the valves ascend the sleeves 31 will remain in contact with the mouths of the bottles until the inclined margins of the disks engage the valve seats 33 when the further movement upward of the cross head will raise the sleeves and leave the bottles free so that the automatic action of the carrier gears will move the car one step to bring another row of empty bottles beneath the outlet tubes. It may be desirable to continue the track upon which the car runs to some distance from the machine and several cars may be in service so that the filling process may be uninterrupted.

It is obvious that many changes may be made in the devices of my invention as herein disclosed without departing from the spirit and scope thereof and I do not wish, there- 125 130

fore, to be limited to the precise construction set forth.

Having thus described my invention what I claim as new and desire to secure by Letters Patent is:—

1. In a bottling machine, the combination with the frame, of a main operating shaft having a pulley mounted thereon, a supply tank and filling tubes provided with suitable valves, a plurality of counter-shafts having geared connection with said main shaft, means for adjusting said connection to vary the speed of the counter-shafts, a bottle conveyer, gearing connecting said counter-shafts with the conveyer, and means connected with said main shaft for operating said valves of the filling tubes.
2. In a bottling machine, the combination with the frame, of a driving shaft, a supply tank, filling tubes, reciprocating sleeves yieldingly mounted upon said tubes, valves for said sleeves provided with tubular stems, means for reciprocating said sleeves, said means consisting of a cross-head adapted to move vertically, connection between the cross-head and said valve stems, and gearing connecting the cross-head with the said driving shaft.
3. In a bottling machine, the combination with the frame, of a driving shaft, a supply tank, filling tubes opening into said tank, reciprocating sleeves slidably mounted upon said tubes, springs for said sleeves, valves situated in said sleeves and provided with tubular stems projecting axially through said tubes, a cross-head attached to said stems and adjustable means for reciprocating said cross-head.
4. In a bottling machine, the combination with the frame, of a driving shaft, a supply tank, filling tubes communicating with said tank, of spring held sleeves slidably mounted upon said tubes, valves arranged in said tubes and having tubular stems projecting through the tubes, a cross-head attached to said stems, and means for reciprocating said cross-head, said means consisting of pitman rods, crank gears for operating said rods, and operative means connecting said crank gears with the main driving shaft.

5. In a bottling machine, the combination with a frame, a driving shaft, a supply tank and filling tubes, of a carriage provided with wheels, gearing connection between said carriage and the driving shaft, means for varying the rate of movement of said carriage, slidable sleeves mounted upon said tubes and provided with gaskets, valves arranged in the sleeves and furnished with tubular stems projecting axially through said tubes, a movable cross-head attached to said stems and means for operating said cross-head.

6. In a bottling machine, the combination with the frame, of an operating shaft carrying a driving pulley, a supply tank, filling tubes communicating with said tank and provided with valves, a carriage mounted upon wheels, a rack attached to the carriage, counter-shafts carrying gears adapted to mesh with said rack, gearing connecting said counter shafts and operating shaft, means for varying the speed of said counter-shafts relative to the operating shaft, and means for operating said valves alternately with the movements of said carriage.

7. In a bottling machine, the combination with the frame, of an operating shaft, a supply tank, filling tubes, valves for the tubes, a carriage furnished with wheels and adapted to be moved in a positive direction, a rack attached to the carriage, counter-shafts carrying gears adapted to mesh with said rack, means for operating the counter-shafts from the operating shaft, means for varying the speed of said counter shafts relatively to the operating shaft, slidable sleeves mounted upon said filling tubes and provided with gaskets, valves for the sleeves, said valves having tubular stems projecting axially through said tubes, a movable cross-head attached to said valve-stems, and adjustable means for operating said cross-head.

In testimony whereof I affix my signature in presence of two witnesses.

LARS JENSEN.
